UNITED STATES PATENT OFFICE.

TASKER HENDERSON, OF DES MOINES, IOWA.

TACKLING-DUMMY RELEASER.

Application filed February 1, 1926. Serial No. 85,393.

The object of my invention is to provide a tackling dummy releaser of very simple, inexpensive and durable and efficient construction.

5 It is my object to provide such a releaser which will release the dummy when it is tackled and which is provided with simple mechanism, whereby the tension of the holding means may be varied or regulated for 10 the purpose of determining the resistance to the releasing action.

With these and other objects in view, my invention consists in the construction, arrangement and combination of the various 15 parts of my tackling dummy releaser, whereby the objects contemplated are attained, as hereinafter more fully set forth, pointed out in my claims, and illustrated in the accompanying drawings in which:

20 Figure 1 is a perspective view of a tackling dummy releaser embodying my invention as assembled for use; and

Figure 2 is a front elevation of the releaser alone.

25 It is now the common practice in coaching men for football games to use a tackling dummy.

The purpose is to enable the player to tackle the dummy under conditions simulating as nearly as possible those of a football 30 game. The dummy can be used without bruising or injuring the squad and can be varied in height and arrangement to suit a great variety of circumstances.

35 One highly desirable quality in a tackling dummy is that it shall be releasable from whatever holds it in order that it may be dropped to the ground in much the same manner as a player would be when tackled.

40 It has been difficult to provide a releaser which would always operate to release the dummy and which could be regulated to afford variation in the desired resistance to the releasing operation.

45 I have provided a releaser in which these desirable results are attained.

In the accompanying drawings, I have used the reference character A to indicate generally a releaser embodying my invention.

50 This releaser preferably comprises a piece of flat spring steel, which for purposes of illustration and in devices, which I have heretofore made and sold, is one and one-

fourth inches wide by one-fourth of an inch 55 thick.

This strap or bar of steel is bent at the middle to form a loop indicated by the character 10 extending perhaps substantially 300° around a circle, and then having the 60 pair of strap members inclined away from each other, as at 11, thence (viewing the device as in position for use) downwardly in parallel portions 12, as shown in Figure 2.

The opposite members of the bar or strap 65 are then inclined inwardly toward each other as at 13 and at their adjacent ends are turned downwardly, as at 14.

At the points where the portions 13 end 70 at their lower parts and the portions 14 begin, they form roughly a V to receive the dummy holding hook. This hook is a double-ended hook, comprising a central shank member 15, having an angular hook 16 at its upper end adapted to have its central 75 portion received in the V, which I have indicated at V in Figure 2.

Formed on the shank at the lower end 80 thereof is an ordinary hook member 17, which may be inserted through a loop 18 on the tackling dummy 19.

A retaining loop or the like 20 may be pivoted to the end of the hook 17 and arranged so that it may be swung inwardly 85 but not outwardly because of the contact with the shank 15 for holding the ring 18 against accidental removal.

A short bolt 21 is swiveled in the upper, central portion of the loop 10 and has a nut 22 on one end and an eye 23 on the other 90 end.

The releaser may be supported on a cross bar 24 or the like in any suitable way as by means of a screw eye 25 or a hook or otherwise.

Extended through the members 12 substantially midway between their ends is a bolt 26 on which may be mounted the wing nut 27.

It will be seen that I have provided a releaser comprising the loop 10 and the parallel arms or portions 12 connected with the loop 10 by the contracted neck formed by the portions 11 and parts of the loop 10.

At the opposite ends of the arms 12 are 105 the in-turned portions 13 and the down-turned ends 14.

When the hook member 16 is dropped in-

to the **V** between the members 13 and a dummy 19 is supported thereby, the hook member 16 rests deep enough in the **V** so that when the dummy 19 is tackled with considerable force, the portions 13 and the arms 12 will be sprung apart far enough to release the hook 16 and allow the dummy to be dropped to the ground.

It will be seen that the tension imposed on the device for resisting the releasing operation may be easily and simply regulated by tightening or loosening the wing nut 27 on the bolt 26.

By providing the loop 10 and the neck 15 between that loop and the arms 12, I find that I can get a considerable variation in this tension, so as to cause the dummy to be released with such application of force, as I may desire to have used for the purpose.

This feature is also important in making it possible to employ the same dummy for high school and grade school boys and for college and university men.

All that is necessary to restore the device to operative position, after the dummy has been released, is to again place the hook 16 with the dummy supported on the hook 17 in the **V**.

I find that the device works satisfactory regardless of the direction from which the dummy is struck.

There is, of course, always a considerable down pull on the dummy when it is being tackled.

The advantages of such a tackling dummy releaser are largely obvious from the foregoing description of its construction and use.

The device is very simple in construction. It is easy to assemble and understand. It operates accurately and effectively for releasing the dummy and the tension imposed upon it for determining the resistance of the releasing operation can be readily and easily regulated.

The releaser can be supported almost anywhere where an overhead bar or support can be made available.

It can, of course, be readily and easily transported from place to place.

The whole releaser weighs only a few pounds.

I claim as my invention:

1. In a tackling dummy releaser, a pair of resilient arms connected together at one end and inclined toward and to each other at their lower ends and provided at their lower adjacent ends with downwardly inclined portions forming substantially a **V**, a detachable member having a portion adapted to be received in said **V** and a portion adapted to hold the tackling dummy, said arms being arranged to hold their lower ends together under tension.

2. In a tackling dummy releaser, a pair of

resilient arms connected together at one end and inclined toward and to each other at their lower ends and provided at their lower adjacent ends with downwardly inclined portions forming substantially a **V**, a detachable member having a portion adapted to be received in said **V** and a portion adapted to hold the tackling dummy, said arms being arranged to hold their lower ends together under tension, and means for varying such tension.

3. In a tackling dummy releaser, a pair of resilient arms connected together at one end and inclined toward and to each other at their lower ends and provided at their lower adjacent ends with downwardly inclined portions forming substantially a **V**, a detachable member having a portion adapted to be received in said **V** and a portion adapted to hold the tackling dummy, said arms being arranged to hold their lower ends together under tension, and means for varying such tension, said means comprising a bolt extended between the arms, and a nut adjustable on said bolt for drawing the arms together.

4. In a tackling dummy releaser, a spring steel strap or bar having at its upper, central portion, a loop with a contracted neck at one end and having arms extending downwardly from said neck and provided with portions at their lower ends inclined toward each other and then downwardly, said device being resilient for holding the lower ends of the device together under tension.

5. In a tackling dummy releaser, a spring steel strap or bar having at its upper, central portion, a loop with a contracted neck at one end and having arms extending downwardly from said neck and provided with portions at their lower ends inclined toward each other and then downwardly, said device being resilient for holding the lower ends of the device together under tension, and means for varying said tension.

6. In a tackling dummy releaser, a spring steel strap or bar having at its upper, central portion, a loop with a contracted neck at one end and having arms extending downwardly from said neck and provided with portions at their lower ends inclined toward each other and then downwardly, said device being resilient for holding the lower ends of the device together under tension, a releasable device having at one end a hook adapted to overlie the said inclined portions, and a means for supporting a weighted member.

7. In a tackling dummy releaser, a spring steel strap or bar having at its upper, central portion, a loop with a contracted neck at one end and having arms extending downwardly from said neck and provided with portions at their lower ends inclined toward each other and then downwardly, said device being resilient for holding the lower

ends of the device together under tension, and means for varying said tension, a releasable device having at one end a hook adapted to overlie the said inclined portions, and a

5 means for supporting a weighted member.

8. In a tackling dummy releaser, a spring steel strap or bar having at its upper, central portion, a loop with a contracted neck at one end and having arms extending down-

10 wardly from said neck and provided with

portions at their lower ends inclined toward each other and then downwardly, said device being resilient for holding the lower ends of the device together under tension, and means for varying said tension, said means comprising a bolt extended through said arms and having an adjustable member on one end.

Des Moines, Iowa, November 12, 1925.
